PORTABLE SPRING-BOARD FOR GYMNASTS

Robert M. Fenner and Donald E. Hamilton, both of
3200 S. Zuni St., Englewood, Colo.

Filed Nov. 23, 1964, Ser. No. 82,745

Term of patent 14 years

(Cl. D34—5)

The figure is a perspective view of a portable spring-board for gymnasts showing our new design.

The opposite side is substantially similar in appearance to that shown.

We claim:

The ornamental design for a portable spring-board for gymnasts, as shown and described.
